ELECTRIC SIGNAL SYSTEM

Filed Sept. 8, 1927

UNITED STATES PATENT OFFICE

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC SIGNAL SYSTEM

Application filed September 8, 1927. Serial No. 218,212.

This invention relates to signal systems, and more particularly to an electric signal system adapted for use on railway trains.

An object of my invention is to provide an electric train signal system by the use of which a trainman may signal the engineman from any car of a train and by which the engineman may cause his reply signal to be transmitted to the car station from which the trainman's signal originated and further by which the engineman may signal all of the car stations on the train.

Another object of the invention is to provide an electric signal system for railway trains in which each of a plurality of vehicles of a train is provided with two electrically controlled signal indicating devices adapted to be supplied with electric current from a source common to both, but each having means associated therewith which renders one subject to current flowing in one direction only, and the other, to current flowing in the opposite direction, the directional flow of current being directly controlled from another vehicle of the train.

These and other objects will appear in the following more detailed description of the invention.

In the accompanying drawing, the single figure is a diagrammatic view of a train signal system embodying my invention.

According to my invention, the locomotive or controller car of a railway train is provided with a source of electric current such as a battery 1, an engineman's switch having spaced contact arms 2 and 3 and spaced contact points 4, 5 and 6, and is further provided with a signal indicating device such as an electric buzzer 7.

The contact points 4 and 6 are connected to ground at 8 and 9 respectively, while the contact point 5 is connected to the train wire 10 which may extend throughout the length of the train. One terminal of the buzzer 7 is connected to the train wire 10 and the other terminal to ground at 11. The switch arms 2 and 3 are connected to the positive and negative terminals respectively of the battery 1, such arms being movable by the engineman to positions in which they will contact with

the contact points 4 and 5 respectively, to connect the positive terminal of the battery to ground 8 and the negative terminal of the battery to the train wire 10 and also being movable to positions in which they will contact with the contact points 5 and 6 respectively, to connect the positive terminal of the battery to the train wire 10 and the negative terminal to ground 9. These switch arms are normally out of contact with the contact points 4, 5 and 6 and are yieldably held in such positions by springs 12.

Each car of the train may be provided with two signal indicating devices such as electric buzzers 13 and 14. One terminal of the buzzer 13, on each car, is connected to ground at 15, while the other terminal is connected to the train wire 10, there being a rectifier 16 interposed in the latter connection for permitting an electric current to flow only in the direction as indicated by the arrow 17. One terminal of the buzzer 14, on each car, is connected with the train wire 10, there being a rectifier 18 interposed in the connection for permitting an electric current to flow only in the direction as indicated by the arrow 19. The other terminal of this buzzer 14 is connected to a terminal contact 20 embodied in the casing 21 of a trainman's switch, with which, each car of the train may be equipped.

The casing 21 of the trainman's switch contains a sliding contact member 22 having an operating stem 23 adapted to be operated by a lever 24 having operating arms 25 and 26, each arm having an operating cord 27 connected therewith. Mounted on the casing, there are fulcrum pins 28 and 29 which are so disposed that when the arm 25 is operated, the lever 24 turns about the fulcrum pin 28 and when the arm 26 is operated the lever 24 turns about the fulcrum pin 29, in either case the stem 23 is operated.

The contact member 22 is provided with contacts 30 and 31 and is normally maintained in the position shown in the drawing, by the action of a spring 32 mounted in the casing 21. This member 22, when moved a predetermined distance, engages a yielding stop member 33, which is subject to the pressure of a spring 34. In order to prevent rota-

tive movement of the contact member 22, a guide bushing having screw-threaded engagement with the casing 21, is provided with a pin 35 which engages in a groove formed in the contact member.

- 5 The contact 30 controls circuit wires connected to the terminal contact 20, and to a terminal contact 36, connected to ground at 37. The contact 31 controls circuit wires connected to a terminal contact 38 connected to the train wire 10, and to a terminal contact 39 connected to the positive terminal of a battery 40 or other source of electric current which is located on each car.
- 10 15 In each car of the train, a jack may be provided, having spaced tines 41 and 42, the tine 41 being connected to the wire leading from the terminal contact 36 to ground 37, and the tine 42 being connected to the wire leading from one terminal of the buzzer 14 to the terminal contact 20. To electrically connect these tines, a plug 43 may be employed, which, when inserted between them, causes the buzzer 14 to be connected to ground 37. The plug 43 is inserted between the tines of the jack on each car of the train at which it is desired to receive signals transmitted by the engineman.

Assuming the several parts of the invention to be in their normal positions as shown in the drawing, and the trainman desires to signal the engineman the trainman pulls the operating cord 27 until the contact member 22 engages the stop member 33, in which position, the contact 31 connects the contact terminals 38 and 39, which permits current to flow from the positive terminal of the battery 40, through the train wire 10 and buzzer 7 to ground 11 and as the negative terminal of this battery is connected to ground at 44, a circuit is completed so that the buzzer 7 on the locomotive will operate.

If the trainman desires to receive the engineman's reply signal at the car station from which he initiated his signal, he causes the contact member 22 to be moved to its second position in which the contact 30 connects the terminal contacts 20 and 36, thus connecting one terminal of the buzzer 14 to ground 37. When the contact member 22 is in this position the contact 31 will have been moved out of connecting engagement with the terminal contacts 38 and 39 so that the battery 40 will not be connected to the train wire 10. If the trainman does not wish to hold the contact member 22 in its second position while awaiting the engineman's signal, he inserts the plug 43 between the tines 41 and 42 of the jack, thus forming a connection from one terminal of the buzzer 14 to ground 37, then releasing his pressure on the operating cord 27, permits the springs 33 and 34 to move the contact member back again to its normal position shown in the drawing, in which position none of the terminal contacts,

associated with the casing, will be connected together. The trainman may, if he so desires, insert plugs 43 in the jacks of any number of cars on which he desires the engineman's reply signal to be sounded.

To reply to the trainman's signal, the engineman moves the switch arms 2 and 3 to positions in which they contact with the switch points 5 and 6, respectively, thus connecting the positive terminal of the battery 1, on the locomotive, to the train wire 10 and the negative terminal to ground 9, which permits current to flow from the battery through the train wire 10 and through the rectifier 18 in the direction of the arrow 19 and through the buzzer 14 to ground 37, which current causes the buzzer to operate. If the trainman has plugs 43 inserted in the jacks of a plurality of cars, the buzzers 14 on all of these cars will operate.

If the engineman desires, he may cause his signal to be sounded on every car of the train, independent of the trainman's switch or the trainman's jack, and this is accomplished by the engineman moving the switch arms 2 and 3, toward the left, into contact with the switch points 4 and 5, respectively, which causes the positive terminal of the battery 1 to be connected to ground 8 and the negative terminal to the train wire 10, which permits current from the battery to flow through ground 8 on the locomotive, and ground 14 on a car and through the buzzer 13 and through the rectifier 16 in the direction as indicated by the arrow 17 to the train wire 10, and the current flowing in this direction will cause the buzzers 13 on all of the cars to operate.

It will be noted that when the switch arms 2 and 3 contact with the switch points 5 and 6, the rectifier 18 will permit a current from the battery 1 to flow through the buzzer 14, and the rectifier 16 will prevent this current from flowing to the buzzer 13. When the switch arms contact with the switch points 4 and 5, the direction of the flow of current from the battery 1 is reversed, so that the buzzer 13 on each car of the train will operate, the rectifier 18 on each car preventing the current flowing in this direction from operating the buzzer 14.

When the engineman operates his switch to reply to the trainman's signal or when the engineman initiates a signal to sound on each car of the train, the buzzer 7, on the locomotive, being connected to the train wire 10 and to ground 11, will also be caused to operate.

Having now described my invention, what I claim as new and desire to secure by Letters Patent, is:—

1. In a train signal system, the combination with a train wire, of a signal device on the head vehicle of a train and connected to said train wire and to ground, two signal

devices on each of the other vehicles of the train, one of the two devices on each vehicle being permanently connected to ground, a switch device on each of the second mentioned vehicles operative to connect each of the other of the two signal devices to ground, a source of current on the head vehicle normally disconnected from said train wire and ground, a source of current on each of the other vehicles permanently connected to ground, a switch device on the head vehicle for controlling the directional flow of current from the source of current on the head vehicle to said train wire, means interposed in the connection from one of the signal devices on each of the second mentioned vehicles to said train wire and adapted to permit current flowing in one direction to operate said device, and means interposed in the connection from the other signal device on each of the second mentioned vehicles to said train wire and adapted to permit current flowing in the opposite direction to operate said device when cut into circuit by the local switch, and a source of current on each of the second mentioned vehicles adapted to be cut into circuit with the signal device on the head vehicle when the switch device on any of the second mentioned vehicles is operated to an other position.

2. In a train signal system, the combination with a train wire, of a signal indicating device on the head vehicle of a train and permanently connected to said train wire and to ground, two signal indicating devices on each of the other vehicles of the train permanently connected to said train wire, one of the signal indicating devices on each of the second mentioned vehicles being permanently connected to ground, a switch device on each of the second mentioned vehicles operative to connect the other one of said signal indicating devices to ground, a source of current on the head vehicle, a rectifier connected to each of the signal devices on each of the second mentioned vehicles, one of said rectifiers on each vehicle being non-resistant to current flowing in one direction and the other being non-resistant to current flowing in the opposite direction, means on the head vehicle operative to control the directional flow of current to the signal devices on the second mentioned vehicles, a source of current on each of the second mentioned vehicles permanently connected to ground adapted to be connected in circuit with the signal device on the head vehicle by the operation of the switch on any of the second mentioned vehicles to another position.

3. In a train signal system, the combination with a train wire, of two signal devices on each vehicle of a train and connected to said train wire, one of said devices on each vehicle being permanently connected to ground and the other being normally disconnected

from ground, a switch on each of said vehicles operative to connect one of the last mentioned signal devices to ground, a rectifier interposed in the connection from each of said signal devices to said train wire, one of the rectifiers being adapted to resist an electric current flowing in one direction and the other being adapted to resist an electric current flowing in the opposite direction, a source of current on another vehicle of the train normally disconnected from said train wire and ground, and means on the last mentioned vehicle operative to connect said source to said train wire and ground to control the directional flow of current from said source for operating said signal devices selectively.

4. In a train signal system, the combination with a train wire, of two signal devices on each vehicle of a train and connected to said train wire, one of said devices on each vehicle being permanently connected to ground and the other being normally disconnected from ground, a switch on each of said vehicles operative to connect one of the last mentioned signal devices to ground, a rectifier interposed in the connection from each of said signal devices to said train wire, one of the rectifiers on each vehicle being adapted to resist an electric current flowing from ground and the other being adapted to resist an electric current flowing from said train wire, a source of current on another vehicle of the train, and means operative to control the directional flow of current from said source for operating one or the other of said signal devices.

5. In a train signal system, the combination with a train wire, of two signal devices on each vehicle of a train and connected to said train wire, one of said devices on each vehicle being permanently connected to ground, manually operative means on each vehicle for cutting the other of said devices on the same vehicle into and out of circuit with ground, rectifiers interposed in the connections from the signal devices on each vehicle to said train wire, one of said rectifiers on each vehicle being adapted to resist an electric current flowing in one direction and the other being adapted to resist an electric current flowing in the opposite direction, a source of current on the head vehicle of the train normally disconnected from said train wire and ground, a switch on the head vehicle operative to one position to connect said source of current to said train wire and to ground to direct a current in one direction to operate one set of said signal devices, and operative to another position to connect said source of current to said train wire and ground to direct a current in the opposite direction to operate the other of said signal devices only when cut into circuit.

6. In a train signal system, the combination with a train wire, of two signal devices on each vehicle of a train and connected to said train wire, one of said devices on each vehicle
